UNITED STATES PATENT OFFICE.

WALTER A. SHEEK, OF LONG BEACH, CALIFORNIA, ASSIGNOR TO INTERNATIONAL PRECIPITATION COMPANY, OF LOS ANGELES, CALIFORNIA, A CORPORATION OF CALIFORNIA.

APPARATUS FOR ELECTRICAL PRECIPITATION OF SUSPENDED PARTICLES FROM GASES.

Application filed February 20, 1922. Serial No. 537,994.

To all whom it may concern:

Be it known that I, WALTER A. SHEEK, a citizen of the United States, residing at Long Beach, in the county of Los Angeles 5 and State of California, have invented a new and useful Apparatus for Electrical Precipitation of Suspended Particles from Gases, of which the following is a specification.

10 This invention relates to means for removing suspended material from gases by passing such gases between electrodes maintained at high potential difference. The main object of the present invention is to provide 15 improved means for removing from the electrodes material deposited thereon.

The accompanying drawings illustrate embodiments of my invention, and referring thereto:

20 Fig. 1 is a horizontal section on line 1—1 in Fig. 2 of a precipitator provided with my improved cleaning means.

Fig. 2 is a section on line 2—2 in Fig. 1.

Fig. 3 is a section on line 3—3 in Fig. 1.

25 Fig. 4 is a detail section on line 4—4 in Fig. 3.

Fig. 5 is a detail section on line 5—5 in Fig. 4.

30 Fig. 6 is a side elevation of a modified form of operating device for the cleaning means.

Fig. 7 is a detail vertical section of another modification.

The precipitator shown in the drawing 35 comprises a flue or chamber 1 adapted for passage of gases therethrough, collecting electrodes 2 mounted in said chamber or flue, and discharge electrode elements 3 extending between or in alternation with and opposite said collecting electrodes. The collecting electrodes may consist of plates or screens of extended area, hung from the top of the flue and extending parallel to the gas flow, and the discharge electrodes may con-

40 sist of elements of relatively small area mounted in frames 4 which are supported on beams 5 carried by insulators 6. I have shown the discharge electrode elements as horizontal rods mounted in vertical frames

45 4, but any other suitable form of discharge electrode elements may be used. The discharge electrodes are mounted to permit of lateral motion, so as to enable them to be

50 moved against the collecting electrodes. For this purpose the supporting frames 4 of the discharge electrode elements may have side bars 8 formed of round pipe, adapted to rest in concave seats or saddles 9 in the beams 5, so that the frames 4 can rock or oscillate. The frames 4 are preferably connected together at their lower ends by tie bars 10. Normally the discharge electrodes are held 55 in stationary position between the collecting electrodes, by the action of gravity or by mechanical retaining means, but when the electrodes are to be cleaned the discharge electrodes are moved laterally to bring them into violent contact with the collecting electrodes, so as to clean all the electrodes by the 60 same operation. This movement of the electrodes may, if desired, be effected manually, or it may be effected automatically by the means shown in Figs. 1 and 2, comprising a 65 pair of rocking levers 12 pivoted on a casing 13 extending laterally from flue 1, said rocking lever carrying insulators 14 attached to the respective tie bars 10 and said levers having pivoted thereto links 15 having notches 16 adapted to engage crank pins 17 on a shaft 18 which is driven by connection 70 to a motor 19, or otherwise. Links 15 are connected by a bar 20 so as to move in unison, and are normally held in elevated position by counterbalance means 16, so as 75 to be out of engagement with crank means 17, and to bring a notch 22 in link 15 into engagement with a shoulder means 23 on the casing 13, to hold the discharge electrodes in centered position. By lowering the links 15, for example, by a handle 24 on 80 one of said links, they may be held in engagement with the operating cranks 17 to cause oscillation of levers 12 and of the discharge electrodes operated thereby. Other operating means may be used, for example, 85 as shown in Fig. 6, the tie bars 10 may be connected directly to a link 15' releasably engaging the operating crank means 17, said link being of insulating material. In this case the discharge electrodes may be normally centered by means of a pin 26 releasably mounted on an insulator 27.

The discharge electrode system is connected by a wire 28 to any source of high potential preferably unidirectional, although 100 alternating potential may be used if desired.

A switch or circuit-breaker 29 is shown as included in the energizing connection for the precipitator, to enable the current to be shut off when the electrodes are being 5 cleaned. The collecting electrodes are preferably grounded.

In the operation of the apparatus, the gases to be treated are passed through the flue or chamber 1 and a high potential difference being maintained between the electrodes, material suspended in the gases is caused by electrical action, to deposit on the electrodes. From time to time, when the electrodes require cleaning, the current is 10 shut off, and the operating mechanism is brought into operation, by lowering links 15 to cause them to engage and be operated by the crank pins 17. The resulting lateral oscillation of the discharge electrodes causes 20 them to strike or impinge on the collecting electrodes with sufficient force to dislodge deposited material from both the collecting and the discharge electrodes. The links may then be released and are automatically raised 25 and are held in position by means 23, to center or space the discharge electrodes with reference to the collecting electrodes.

It will be understood that my invention 30 consisting in the provision for cleaning the electrodes by carrying certain of them to swing against certain others, is not limited to any particular construction of the electrodes, or arrangement of the electrodes, with respect to the gas stream. Thus, the 35 gas stream may be caused to pass vertically or horizontally between the electrodes, or by contacting with the collecting and the discharge electrodes so as to be pervious to the gases, the gas stream may be caused to

pass through, instead of between the electrodes.

It is obvious that the relative movement of the discharge and collecting electrodes required for bringing them into contact may be effected by moving either or both of the 45 sets of electrodes. Thus, as shown in Fig. 7, the collecting electrodes 2 may be mounted to rock on bearings 9' so as to strike the discharge electrodes 3, and may be operated by direct connection to operating means, 50 such as a handle 30.

What I claim is:

1. In an electrical precipitator for removing suspended material from gases opposing electrodes one of which is movably mounted to swing toward or from the other electrode, and means for moving said movably mounted electrode to bring it against the other electrode so as to jar both electrodes.

2. A construction as set forth in claim 1 and comprising, in addition, means for normally holding said movably mounted electrode in stationary position, spaced from the opposing electrode.

3. An electrical precipitator comprising a gas receiving chamber, parallel collecting electrodes mounted in said chamber, insulated discharge electrodes mounted in said chamber and extending between the respective collecting electrodes and adapted to be moved laterally into contact with the collecting electrodes, and means for moving said discharge electrodes laterally.

In testimony whereof I have hereunto subscribed my name this 7th day of February, 1922.

WALTER A. SHEEK.
